UNITED STATES PATENT OFFICE.

WILLIAM B. SHOTWELL, OF PETERSBURG, KENTUCKY, ASSIGNOR OF ONE-HALF TO SOLON EARLY, OF PETERSBURG, KENTUCKY.

FENCE-CLAMP.

No. 889,819.

Specification of Letters Patent.

Patented June 2, 1908.

Application filed August 14, 1907. Serial No. 388,524.

To all whom it may concern:

Be it known that I, WILLIAM B. SHOTWELL, a citizen of the United States of America, residing at Petersburg, in the county of Boone and State of Kentucky, have invented new and useful Improvements in Fence-Clamps, of which the following is a specification.

This invention is an improved fence clamp, and it consists in the construction, combination and arrangement of devices hereinafter described and claimed.

In the accompanying drawings, —Figure 1 is a perspective view of a fence clamp constructed in accordance with this invention.

Fig. 2 is a sectional view of the same. Fig. 3 is a side elevation of the same showing the clamp open.

The two members 1 and 2 of the clamp are connected together at one end by a hinge 3. The member 1 is provided with a plurality of keepers 4, here shown as bolts extending therethrough and projecting from one side thereof, which I will term the inner side, and having slots 5 in the said projecting ends. The member 2 is provided with openings 6, through which the said slotted ends of the keepers extend when the said members 1 and 2 are closed together, on opposite sides of the fence wires, to clamp the fence wires between them. Said member 2 is provided on its outer side with reinforce strips 7 which are preferably made of sheet or plate metal, and on one of said reinforce strips at points opposite the slotted ends of the keepers are guides 8 in which are wedge-shaped keys 9. Said

wedge-shaped keys may be forced into the slots 5 of the bolts to lock the members 1, 2 of the clamp on opposite sides of the fence wires or fabric, as will be understood. The said keys are connected together by a bar 10 which has parallel arms 11 that operate in staples or other suitable guiding devices 12. The said bar prevents loss of any of the keys, the arms 11 thereof having their ends turned at right angles, as at 13, to form stops which by coaction with the staples 12 prevent the said arms from being withdrawn from said staples.

Having thus described the invention, what is claimed as new, is:—

A fence clamp comprising a pair of members one provided with openings and the other provided with keepers to extend through such openings and having slots, a reinforce strip on the last mentioned member having guides, wedge shaped keys in such guide to engage the slots of the keepers to clamp said members together, guiding devices on the last mentioned member and a rod connecting said keys together, having arms operating in said guide devices and further provided with stops to coact on the said guiding devices to prevent said arms from being withdrawn.

In testimony whereof I affix my signature in presence of two witnesses.

WILLIAM B. SHOTWELL.
